(57) **CLAIM**

The ornamental design for a batter's helmet, as shown and described.

DESCRIPTION

FIG. 1 is a perspective rear view of the batter's helmet in accordance with the design of the present invention;

FIG. 2 is a top plan view of the batter's helmet of FIG. 1; FIG. 3 is a bottom plan view of the batter's helmet of FIG. 1;

FIG. 4 is an elevational view from one side of the batter's helmet of FIG. 1;

FIG. 5 is an elevational view from the other side of the batter's helmet of FIG. 1;

FIG. 6 is a front end elevational of the batter's helmet of FIG. 1; and,

FIG. 7 is a rear end elevational view of the batter's helmet of FIG. 1.

The details shown in broken lines are for illustrative purposes only and form no part of the claimed design.
